Primary Examiner — David Muller(74) *Attorney, Agent, or Firm* — Mark D. Wieczorek; Mayer & Williams PC**(57) CLAIM**

The ornamental design for the cell encapsulation device, as shown.

DESCRIPTION

FIG. 1 is a perspective view of a first embodiment of the cell encapsulation device.

FIG. 2 is a top plan view thereof;

FIG. 3 is a bottom plan view thereof;

FIG. 4 is a left side elevational view thereof;

FIG. 5 is a right side elevational view thereof;

FIG. 6 is a rear elevational view thereof;

FIG. 7 is a front elevational view thereof;

FIG. 8 is a perspective view of a second embodiment of the cell encapsulation device.

FIG. 9 is a top plan view thereof;

FIG. 10 is a bottom plan view thereof;

FIG. 11 is a left side elevational view thereof;

FIG. 12 is a right side elevational thereof;

FIG. 13 is a rear elevational vie thereof; and,

FIG. 14 is a front elevational view thereof.
